United States Patent

Des. 242,462

Patented Nov. 23, 1976

242,462

COVER FOR A VENT OPENING

Sidney J. Shames, 57 Holly Place, Briarcliff Manor, N.Y.
10510, and Harold Shames, 5 Agnes Circle, Ardsley,
N.Y. 10502

Filed Dec. 22, 1975, Ser. No. 643,093

Term of patent 14 years

Int. Cl. D23—04

U.S. Cl. D23—154

Fig. 1.

Fig. 2.

Fig. 3.

FIG. 1 is a side elevational view of a cover for a vent opening embodying our new design;

FIG. 2 is a plan view of the front side thereof; and FIG. 3 is a plan view of the rear side thereof.

We claim:

The ornamental design for a cover for a vent opening, as shown and described.
